TELEPHONE SYSTEM

John Wicks, Oak Park, Ill., assignor to Associated Electric Laboratories, Inc., Chicago, Ill., a corporation of Delaware

Application June 30, 1939, Serial No. 282,006

19 Claims. (Cl. 179—18)

The present invention relates to automatic telephone systems and has for one of its objects the provision of improved apparatus for automatically forwarding calls intended for a first substation of an automatic telephone system to another substation selected by the subscriber or party for whose service the first substation is provided.

It is another object of the invention to provide in an automatic telephone system, improved call forwarding apparatus of the character described which is economical to manufacture and install, is adapted for use in conjunction with automatic switching apparatus of substantially all types, and is thoroughly reliable in operation.

It is another object of the invention to provide in an automatic telephone system, improved call forwarding apparatus of the character described which is normally inactive and is automatically rendered operative to respond to calls incoming to the associated substation through operation of the apparatus to select a substation to which the calls are to be forwarded.

It is another object of the invention to provide in an automatic telephone system, call forwarding apparatus of the character described which is arranged in an improved manner such that no auxiliary lines are required between the automatic switching apparatus of the system and the substation with which the call forwarding apparatus is associated.

It is a further object of the invention to provide in an automatic telephone system, improved call forwarding apparatus which is so arranged that alternating current pulsing over the line extending to the substation with which the apparatus is associated, is utilized for directly controlling the automatic switching apparatus through which the calls are forwarded; thus eliminating the necessity of providing an auxiliary line between the substation and the automatic switching apparatus of the system.

The invention is illustrated in its embodiment in an automatic telephone system which comprises a plurality of substations and automatic switching apparatus including non-numerical and impulse responsive numerical switches for setting up connections between the lines extending to the substations. Two embodiments of the invention are illustrated. In each modification, call forwarding apparatus is provided individual to the lines arranged for call forwarding service. This apparatus includes a motor-driven, cyclically operative device which is operative to transmit to the automatic switching apparatus the impulses of the directory number designating the substation to which the calls are to be forwarded. This device includes a plurality of control elements individually corresponding to the substations to which calls may be forwarded, a station selecting element having a normal position and

operative to off-normal positions individually corresponding to the control elements, and pulsing means adapted to be controlled by any one of the control elements for transmitting to the automatic switching apparatus the impulses of the directory number designating the substation corresponding to the off-normal position occupied by the station selecting element. For the purpose of initiating the operation of the call forwarding apparatus, there is provided a relay which is adapted to be connected to the line arranged for call forwarding service and to respond to ringing current transmitted over the line. In order to connect this relay to respond to ringing current transmitted over the line, there is provided switching means operative in response to operation of the selecting element to any one of its off-normal positions. This relay functions to complete the operating circuit for the motor which drives the cyclically operative pulsing device, and the arrangement is such that the pulsing device is caused to operate through repeated cycles, thereby repeatedly to forward an incoming call to the associated line through the automatic switching apparatus to the substation selected for call transfer, until the call is abandoned or is answered at the last-mentioned substation. In order to arrest the operation of the device and to terminate the transmission of ringing current over the line associated with the call forwarding apparatus there is provided in this apparatus means operative to perform the indicated functions when the forwarded call is answered at the substation to which the call is routed.

In one embodiment of the invention, the impulses produced through operation of the call forwarding apparatus are transmitted from the associated substation to the automatic switching apparatus of the system over an auxiliary line extending between the substation and the automatic switching apparatus. In the second embodiment of the invention, the use of an auxiliary line is not necessary; the call forwarding apparatus provided at the substation arranged for call forwarding service including means automatically operative in responsive to the presence of an incoming call on the line extending to the substation for transmitting alternating current pulses back over the line. In the line terminating exchange, apparatus is provided which is operative in response to the alternating current pulses to cause a connection to be extended from the line through the automatic switching apparatus to the substation previously selected as the station to which such calls are to be forwarded. More particularly, the cyclically operative device provided at the substation arranged for call forwarding service functions to control means for transmitting over the associated line a

long alternating current pulse followed by alternating current impulses corresponding to the directory number designating the substation to which the calls are to be forwarded. In the line terminating exchange, there is provided a circuit which includes a pulsing relay adapted to be connected to the indicated line to respond to the alternating current pulses and to repeat the switch directing impulses to the automatic switching apparatus. This relay is arranged to be connected across the conductors of the associated line under the control of additional relays which respond to ringing current transmitted over the line.

Further features of the invention pertain to the particular arrangement of the circuit elements described hereinafter, whereby the above and additional operating features are attained.

The novel features believed to be characteristic of the invention are set forth with particularity in the appended claims. The invention, both as to its organization and method of operation, together with further objects and advantages thereof will best be understood by reference to the specification taken in connection with the accompanying drawings in which Figure 1 illustrates one embodiment of the improved call forwarding apparatus and Fig. 2 illustrates a second embodiment of the improved call forwarding apparatus; these two embodiments of the invention being respectively associated with two different subscribers' lines forming a part of the same automatic telephone system.

Briefly described, the system illustrated in the drawings comprises a plurality of substations A, B, C and D individually associated with lines 10, 11, 12 and 13 in the order named; which lines all extend to the automatic switching apparatus provided in the line terminating exchange. This apparatus comprises line switches 14, 15, 16 and 17 individually associated with the lines 10, 11, 12 and 13, a plurality of impulse responsive selector switches including the two switches indicated at 18 and 19, and a plurality of impulse responsive connector switches, two of which are indicated at 20 and 21, respectively. The system further comprises call forwarding apparatus individually associated with the substations B and D, respectively. The arrangement of this apparatus as provided in conjunction with the substation B is such that an auxiliary line 22 extending from this substation to the automatic switching apparatus of the line terminating exchange and an auxiliary line switch 23 for serving the line 22 are required. The call forwarding apparatus illustrated in Fig. 2, in association with the substation D, on the other hand, is such that no auxiliary line extending from this substation to the automatic switching apparatus of the line terminating exchange is required. This apparatus does, however, require the provision of an auxiliary line switch 24 which functions to forward calls to the selector switches of the system.

The line switches 14, 15, 16, 17, 23 and 24 are commonly known as non-numerical switches for the reason that they perform no line selecting operations other than the selection of trunk lines extending to idle ones of the first selector switches. Preferably, these line switches are of the well-known rotary type of which several commercial embodiments are available. The selector and connector switches of the system are commonly known as numerical switches for the reason that they are directly controllable, in acc-

cordance with impulses transmitted thereto, to perform line group, subgroup and particular line selecting operations. Preferably, these switches are of the well-known Strowger type, each having embodied therein a Strowger switching mechanism utilizing vertical and rotary motions in its operation to select an outgoing line. Obviously, the control apparatus embodied in the selector and connector switches is different in each instance depending upon the particular character of the switch.

Neglecting for the present the arrangement of the call forwarding apparatus provided in association with the substations B and D, the system as described above is entirely conventional in form and its mode of operation is well understood in the art. Briefly described, if a subscriber at the substation A, for example, initiates a call intended for the substation B by removing the receiver provided at the substation A from its supporting hook or cradle, a calling loop circuit is completed by way of the line 10 for initiating the operation of the line switch 14. This line switch responds to the completion of the calling loop circuit by operating to select a trunk line extending to an idle one of the first selector switches. If the selector switch 18 is the first available idle selector switch accessible to the line switch 14, the last-mentioned switch, upon testing the condition of the trunk line extending to the selector switch 18 and finding this line to be idle, operates to extend the calling loop circuit to the selector switch. The control apparatus of the seized selector switch 18 now operates to return the usual dial tone signal to the calling subscriber. The selector switch 18 responds to the impulses of the first digit dialed at the substation A by elevating its wipers to a position opposite the level of bank contacts terminating the trunk lines extending to the connector switches having access to the called line 11 and forming the group including the switch 20. Further, the control apparatus of the selector switch operates to terminate the dial tone signal. During the interdigit pause between the first and second digits, the wipers of the selector switch 18 are rotated step-by-step in the usual manner, successively, to test the condition of the trunk lines respectively extending to the connector switches of the selected group. If the connector switch 20 is the first available idle switch of the selected group, the rotary movement of the wipers embodied in the selector switch 18 is arrested when these wipers engage the contacts terminating the conductors of the trunk line incoming to this connector switch. In addition, the control apparatus of the selector switch 18 functions to extend the calling loop circuit to the seized connector switch 20. The connector switch 20 responds to the impulses of the second digit dialed at the calling substation by elevating its wipers to a position opposite the level of bank contacts terminating the group of lines including the called line 11. In response to the impulses of the third digit dialed at the calling substation these wipers are rotated into engagement with the particular set of bank contacts at which the conductors of the line 11 are terminated. Following the selection of the called line in the manner just explained, the control apparatus embodied in the connector switch 20 functions to determine the idle or busy condition of the selected line and to transmit the usual busy tone signal over the calling loop circuit to the calling subscriber in the event the called

line is busy. If the called line is found to be idle, the control equipment embodied in the connector switch functions to transmit ringing current over the called line for the purpose of energizing the ringer conventionally provided at the called substation B and over the calling line to inform the calling party that the called substation is being rung. When the call is answered at the called substation a direct current bridge is connected across the conductors of the line 11, thereby to complete a circuit for energizing the ring cut-off relay conventionally embodied in the control equipment of the operated connector switch. This relay, upon operating, functions to terminate the ringing operation, to arrest the ring-back tone signal and to complete the desired conversational circuit between the calling and called substations. When the ring cut-off relay operates, a loop circuit is established between the connector switch 20 and the substation B, which loop circuit extends through the windings of the back bridge or battery reversing relay conventionally embodied in the connector switch 20. The resulting operation of this back bridge relay causes the direction of current flow over the calling loop circuit to be reversed in the usual manner, and this current reversal may be utilized for various control functions such as call metering or the like. The manner in which the connection is released depends upon the particular arrangement of the control apparatus embodied in the connector switch 20. For example, this apparatus may be so arranged that the operated switch train is released only when the connection is released at both the calling and called substations. Alternatively, the control apparatus of the connector switch 20 may be so arranged that the release of the switch train is entirely under the control of the calling subscriber. Assuming that the latter arrangement is employed, when the calling party replaces the receiver provided at the substation A upon its supporting hook or cradle the calling loop circuit is interrupted with the result that the connector switch 20, the selector switch 18 and the line switch 14 are successively released in the order named and in a manner well understood in the art. When these switches are all restored to normal, the calling and called lines 10 and 11 are marked as idle in the connector switches having access thereto and the apparatus utilized in completing the connection is rendered available for further use. In view of the foregoing description it is believed that the manner in which connections may be established between the other substations of the system will be clearly apparent without further explanation.

Referring now more particularly to the embodiment of the call forwarding apparatus illustrated in Fig. 1 in association with the substation B, this apparatus comprises a cyclically operative control device which includes a plurality of control elements or cams individually corresponding to the substations to which calls incoming to the line 11 may be forwarded. One such cam is indicated at 100, this cam individually corresponding to the substation C associated with the subscriber's line 12. Each of the control elements or cams is notched around its periphery to provide a camming surface for controlling a pair of impulse shunting springs 101, these springs being transversely movable with respect to the cams to engage the peripheral surface of a selected one thereof in unison with a station selecting element 102 as indicated by the dotted unicon-

trol line U. The station selecting element 102 is provided with a pointer portion arranged to cooperate with an index 103 which includes indices identifying the substation corresponding to the position occupied by the shunt springs 101. More particularly, the station selecting element 102 is provided with a normal position and a plurality of off-normal positions individually corresponding to the substations to which the calls may be forwarded. This element is arranged to control a pair of switching springs 104 in a manner such that the springs are disengaged when the station selecting element occupies its normal position and are moved into engagement when this element is operated to any one of its off-normal positions. The control device further comprises an impulsing cam 105 which is arranged to operate a pair of pulsing springs 106. Two additional control elements or cams 107 and 108 are provided, which elements are arranged respectively to control the springs embodied in associated spring piles 109 and 110. For the purpose of driving the enumerated control cams there is provided a small synchronous motor 111 of the self-starting type which is arranged to be energized from the usual commercial frequency 110 volt source. More particularly, this motor is arranged to drive a shaft 112 upon which the control elements 107 and 108 are mounted at a reduced speed through a speed reducing mechanism 113. The shaft 112 is, in turn, geared to drive a shaft 114 upon which the station selecting control elements are mounted through a second speed reducing gear train 115. The shaft 114 is arranged to drive a third shaft 115 which carries the pulsing cam 105 through a speed increasing gear train 116. Since the control cams 107 and 108 are mounted upon the same shaft, these cams are obviously operated in unison, preferably at a speed of approximately one and two-thirds revolutions per minute. The gear ratio of the gear train 115 is such that the station selecting cams carried by the shaft 114 are rotated three revolutions for each revolution of the cams 107 and 108, or at a speed of approximately five revolutions per minute. The gear ratio of the train 116 is such that the impulsing cam 105 is driven at a speed of approximately six hundred revolutions per minute, corresponding to an impulsing rate of approximately ten impulses per second. If desired, the mechanical construction of the portion of the control device comprising the station selecting cams, the gear train 116, the pulsing cam 105 and the station selecting element 102 may be substantially similar to that disclosed in the copending application of Hans Sengbusch, Serial No. 147,831, filed June 12, 1937.

For the purpose of initiating the operation of the control device there is provided an alternating current relay 120 which includes a winding adapted to be bridged across the conductors of the line 11 in series with a condenser 122 in response to operation of the station selecting element 102 to one of its off-normal positions so that it will respond to ringing current transmitted over this line. The line connecting equipment of the call forwarding apparatus includes a repeating coil 123, having a pair of windings 124 and 125 adapted to be connected in series circuit relationship with the condenser 122 and the winding of the relay 120 across the conductors of the line 11 and a second pair of windings 126 and 127 adapted to be included in a calling loop circuit including the auxiliary line 22 and extend-

ing to the line switch 23. The completion of a talking circuit between the lines 11 and 22 is under the control of a polarized back bridged relay 130 which is preferably of the permanent magnet type.

Referring now more particularly to the operation of the call forwarding apparatus illustrated in Fig. 1, it will be apparent that with the station selecting element 102 occupying its normal position such that the contact springs 104 are disengaged, the series path including the windings 124 and 125 of the repeating coil 123 and the winding of the start relay 120 is not connected across the conductors of the line 11. Accordingly, calls incoming to the substation B and routed through the automatic switching apparatus terminating exchange in the manner previously explained, may be completed and released without in any way affecting the call forwarding arrangement. Also, calls originating at the substation B may be completed without interference occasioned by the associated call forwarding apparatus. In order to condition the call forwarding apparatus to operate in response to calls incoming to the line 11, the station selecting element 102 is operated to the off-normal position corresponding to the substation to which the calls are to be routed. For example, if the subscriber at the substation B desires to have his calls forwarded to the substation C during a particular time interval, the station selecting element 102 is operated to the off-normal position corresponding to the substation C, thereby to position the shunt springs 101 to be controlled by the station selecting cam 100. Immediately the element 102 is operated to an off-normal position, the springs 104 are closed to connect across the conductors of the line 11 the series path including the winding of the relay 120.

With the apparatus in this condition if a call intended for the substation B is routed to the line 11 through the switches 14, 18 and 20 from the substation A in the manner previously described, ringing current is projected over the line 11 following the operation of the control apparatus of the connector switch 20 to ascertain the idle condition of the line 11. A portion of the ringing current traverses the winding of the relay 120 over a circuit which may partially be traced as extending by way of the line conductor 11a, the contact springs 104, the winding 124, the winding of the relay 120, the condenser 122, the winding 125 and the line conductor 11b. Each time the relay 120 is energized by current traversing this circuit it operates to complete, at its armature 121, a circuit for energizing the synchronous motor 111, this circuit extending from one terminal of the alternating current source, through the windings of the motor 111, the armature 133 and the armature 121 to the opposite terminal of the current source. When energized over this circuit, operation of the motor 111 to drive the various control cams, previously described, is initiated. During the initial operation of the motor, the cam 107 is moved off-normal to operate the contact springs 134 and 135 respectively into engagement. At the contact springs 135 an auxiliary or second circuit is completed for energizing the motor 111, this second circuit extending from one terminal of the current supply source through the windings of the motor 111 and by way of the contact springs 135 to the opposite terminal of the current source. Thus, operation of the motor 111 is maintained independently of the energized or deenergized

condition of the start relay 120 until the control device driven thereby has been operated through a complete cycle of operation. When the contact springs 134 are moved into engagement a calling loop circuit extending to the line switch 23 is completed, this loop circuit extending by way of the line conductor 22a, the repeater winding 126, the winding of the relay 130, the repeater winding 127, the contact springs 134, 136 and 138 and the opposite line conductor 22b. The direction of current flow over this loop circuit is such that the polarized relay 130 does not operate; this relay being so poled that it only operates in response to the reversal of current flow over the calling loop circuit which occurs when the call is answered at the substation to which the call is forwarded. When the above-traced calling loop circuit is completed, the line switch 23 operates to select an idle one of the selector switches, such, for example, as the switch 19, to which it has access. When this switch is selected, the calling loop circuit is extended thereto and the selected switch is conditioned to respond to the first series of impulses transmitted over the line 22 through operation of the pulsing springs 106 as controlled by the shunt springs 101. In order to provide ample time for the line switch 23 to perform its switch selecting operation, the transmission of impulses from the control device is delayed for a predetermined time interval after operation thereof is initiated. To this end, the springs 136 and 138, controlled by the cam 108, are held in engagement to short-circuit the springs 101 and 106 until the cam 108 has been rotated through an angle of approximately 45 degrees. It will be understood that during such rotation of the cam 101 the station selecting cams, including the cam 100, are rotated through an angle of approximately 135 degrees since the speed ratio between the shafts 114 and 112 is approximately three to one. By virtue of this arrangement, transmission of switch control pulses from the control device is delayed for an interval of approximately four and one-half seconds after the calling loop circuit is completed, this interval being ample for the line switch 23 to test the idle or busy condition of all of the selector switches to which it has access. At the end of this interval, the cam follower portion of the spring 138 drops into the notch 108a provided in the peripheral surface of the cam 108. As a result, the springs 136 and 138 are disengaged and the springs 136 and 137 are moved into engagement. Thus the parallel connected shunt springs 101 and the pulsing springs 106 are effectively included in the calling loop circuit. Shortly following this operation, the cam follower portion of the shunt spring 101a drops into the notch 109a formed in the peripheral surface of the station selecting cam 100. Thus, the shunt springs 101a and 101b are disengaged so that the pulsing springs 106 are actively included in the calling loop circuit to transmit thereover to the selector switch 19 the impulses of the first digit of the directory number designating the substation C. In this regard, it will be apparent that the number of impulses transmitted during the digit is determined by the circumferential length of the notch 109a formed in the peripheral surface of the element of the cam 100. For example, if the directory number designating the substation C is 352, the length of the notch 109a will be so proportioned relative to the pulsing rate and the speed of rotation of the cam 100 that three impulses are

transmitted over the calling loop circuit during the interval when the cam follower portion of the spring 101a is engaging the peripheral surface of the cam 100 defined by this notch. In a similar manner, the length of the second notch 100b corresponding to the second digit of the directory number designating the substation C is formed of a length such that five impulses will be transmitted over the calling loop circuit while the cam follower portion of the spring 101a is engaging the peripheral surface defined by this second notch. Also, the length of the notch 100c which determines the number of impulses of the third digit is such that two impulses are transmitted over the calling loop circuit by the pulsing springs 106 during the interval when the cam follower portion of the spring 101a is engaging the peripheral surface of the cam 100 defined by this third notch.

The selector switch 19 responds to the impulses of the first digit by elevating its wipers to a position opposite the level of bank contacts terminating the conductors of the trunk lines respectively extending to the connector switches having access to the called line 12. When the cam follower portion of the shunt spring 101a engages the projection separating the notch 100a and 100b of the cam 100, it is moved into engagement with the associated spring 101b to complete an obvious path in shunt with the pulsing springs 106 so that the latter springs are no longer actively included in the calling loop circuit. The circumferential length of the projection separating the two notches 100a and 100b determines the duration of the interdigit pause between the first and second digits of the directory number designating the substation C. During this pause, the wipers of the selector switch 19 are rotated step-by-step until a trunk line extending to an idle one of the connector switches of the selected group is found. Assuming, for example, that the connector switch 21 is the first available idle switch of the selected group, the selector switch 19 seizes this connector switch and extends the calling loop circuit thereto. Thereafter, and when the cam follower portion of the shunt spring 101a drops into the notch 100b of the cam 100, the pulsing springs 106 are again actively included in the calling loop circuit so that the impulses of the second digit are transmitted to the connector switch 21. The indicated connector switch responds to the impulses of this digit by elevating its wipers to a position opposite the level of bank contacts terminating the ten subscribers' lines forming the subgroup including the line 12. When the cam follower portion of the spring 101a engages the projection separating the notches 100b and 100c, the shunt springs are again moved into engagement to short circuit the pulsing springs 106, thereby to terminate the impulses of the second digit and to provide an interdigit pause during which the control apparatus of the connector switch 21 is conditioned to respond to the impulses making up the third digit of the directory number designating the substation C. The impulses of this third digit are started when the cam follower portion of the spring 101a drops into the notch 100c so that this spring is disengaged from its associated spring 101b. The connector switch 21 responds to the impulses of the third digit by operating to select the line 12 from the selected subgroup of lines. The pulses of the third and final digit are terminated when the cam follower portion of the spring 101a is moved out of the

notch 100c and into engagement with its associated spring 101b to short circuit the pulsing springs 106. Shortly following the end of the third digit, the cam follower portion of the contact spring 138 moves over the trailing edge of the notch 108a provided in the cam 108 so that the springs 136 and 138 are moved into engagement, following which, the springs 136 and 137 are disengaged. Thus, the shunt springs 101 and the pulsing springs 106 are effectively shunted from the calling loop circuit so that no further impulses may be transmitted thereover until a second cycle of operation of the control device is initiated. After the impulse transmission is ended, the calling loop circuit is not interrupted for a substantial time interval during which the called line 12 is tested to determine the idle or busy condition thereof, ringing current may be transmitted over the line to energize the signal device provided at the called substation and the call may be answered. Thus, the cams 107 and 108 are rotated through an angle of approximately 135 degrees during the interval when the call is being forwarded through the switches 15, 19 and 21 to the called line 12. These cams must be rotated through an additional angle of 225 degrees before they are returned to their respective normal positions to complete the operating cycle. Thus, a period of approximately twenty-four seconds is provided during which the called substation may be signaled and the call answered.

Assuming that the called line 12 is idle at the time it is selected by the connector switch 21 and, further, that the call is answered during the above-mentioned time interval required for the control device to complete its cycle of operation, the ring cut-off relay provided in the connector switch 21 operates to complete a loop circuit extending through the windings of the back bridge relay of this switch and including the conductors of the called line 12 in the usual manner. Upon operating, the back bridge relay of the connector switch functions to reverse the direction of current flow over the loop circuit extending from the connector switch 21 to the repeater 123. As a result, the polarized relay 130 is caused to operate. Upon operating, the relay 130 opens, at its armature 133, a point in the initially completed circuit for energizing the motor 111. At its armature 132, the relay 130 completes an obvious path for short-circuiting the condenser 122, thereby to establish a direct current bridge across the conductors of the line 11. More particularly, a loop circuit is established which extends by way of the conductor 11a, the springs 104, the winding 124, the winding of the relay 120, the armature 132, the winding 125 and the opposite line conductor 11b. When this circuit is completed, the ring cut-off and back bridge relays embodied in the connector switch 20 are caused sequentially to operate in the manner previously explained so that the ringing operation of the connector switch 20 is arrested and a talking circuit is established which includes the repeating coil 123 and extends from the calling substation A to the substation C.

At its armature 131, the back bridge relay 130, upon operating, effectively shunts the contact springs 134 from the loop circuit including the line 22. As a result, this loop circuit is not interrupted when the control cams 107 and 108 are returned to their respective home positions to end the operating cycle of the control device. When the cams 107 and 108 are rotated back to

normal, the cam follower portion of the lower control spring 135 drops into the notch provided in the peripheral surface of the cam 107 so that the springs 134 and 135 are respectively disengaged. When the springs 135 are moved out of engagement, the previously traced second circuit for energizing the motor 111 is interrupted. Accordingly, this motor is deenergized and operation of the control device is arrested with the various cams occupying the positions illustrated in Fig. 1 of the drawings.

Assuming that the connector switches 20 and 21 and the other similar switches embodied in the system are of the calling party release type, when the call is cleared out at the calling substation A the switches 20, 18 and 14 included in the operated switch train are released in the order named and in the manner previously explained. When the connection is cleared out at the called substation C, the back bridge relay embodied in the connector switch 21 is caused to restore so that the direction of current flow over the loop circuit including the line 22, is again reversed. As a result, the polarized relay 130 restores to open the loop circuit at its armature 131. At its armature 132, the relay 130 opens the path short-circuiting the condenser 122. At its armature 133, the relay 130 reprepares the operating circuit for the motor 111. When the loop circuit including the line 22 is thus interrupted, the connector switch 21, the selector switch 19 and the line switch 23 are successively released in the order named. Thus, the automatic switching apparatus utilized in forwarding the connection to the substation C is fully restored to normal.

If, for any reason, the call as forwarded to the substation C is not answered at this substation within the interval required for the control device to complete its cycle of operation after the impulse transmission is ended, the switch train through which the call is forwarded is released and a new cycle of operation of the control device is initiated; assuming that the call is not abandoned at the calling substation A during this interval. Thus, if the called line 12 is busy at the time it is selected by the connector switch 21, the connection obviously cannot be completed. In such case, the control apparatus of the connector switch 21 functions to return busy tone over the loop circuit including the line 22 and extending to the repeating coil 123, in the usual manner. Since, however, no talking circuit is as yet established between the calling line 10 and the repeating coil 123, this busy signal is not transmitted to the calling subscriber. On the contrary, the usual ring-back tone signal is transmitted to the calling substation continuously until the call is abandoned or is successfully completed. Hence, it will be apparent that the calling party may not abandon the call for a substantial period, during which the control device of the call forwarding apparatus may operate through a number of cycles. This may also occur in the case when the line to which the call is forwarded is idle, but the call as forwarded to the substation associated with this line is not answered promptly. In any event, when such a situation arises, the control device upon completing its first cycle of operation interrupts, at the contact springs 134, the loop circuit extending by way of the line 22 to the line switch 23. As a result, the operated switch train comprising the switches 21, 19 and 23 is released. Since the start relay 120 is, under the conditions as-

sumed, still operating intermittently in response to the ringing current being transmitted over the line 11, the motor 111 is deenergized only for a short time interval, if at all, following the completion of the first cycle of operation of the control device. During the first ringing period following the end of the first cycle of operation of the control device, the relay 120 reoperates, the motor 111 is again energized, and a new cycle of operation of the control device is initiated. From this point on, the manner in which the call is again forwarded to the called substation C is exactly the same as explained above.

In the event the call is abandoned at the calling substation A while a cycle of operation of the control device is in progress and before the call is answered at the substation C, the operated switch train through which the call is routed to the line 11 is released, but the control device of the call forwarding apparatus continues to operate until the cycle of operation in progress is completed. Thus, so long as the contact springs 135 are engaged, the secondary circuit for energizing the motor 111 is not interrupted. Accordingly, if the call is abandoned while a cycle of operation of the control device is in progress, the control device continues to operate. In such case, if the call is answered at the called substation C to cause the operation of the polarized relay 130 in the manner previously explained, the called party is informed by the failure of the calling party to respond to his answering salutation that the call has been abandoned, and may cause the operated switch train through which the call is forwarded to the line 12 to be released by restoring the receiver provided at the substation C to its supporting hook or cradle.

The call as routed to the line 11 from the substation A may be answered at the substation B even though the call forwarding apparatus is conditioned to operate in response to ringing current transmitted over the line 11. In such case, the ringing operation of the connector switch 20 is arrested when the party answering the call removes the receiver provided at the substation B from its supporting hook or cradle to establish a direct current bridge across the conductors of the line 11. Since operation of the control device is initiated when ringing current is first transmitted over the line 11, the call forwarding apparatus operates to forward the call to the substation C. If the call is answered at the last-mentioned substation before the control device completes its cycle of operation, a three way connection is established between the substations A, B and C. Completion of the branch connection to the substation C in no way interferes with the release of the call forwarding apparatus or the automatic switches through which the connections are routed.

Referring now more particularly to the embodiment of the call forwarding apparatus illustrated in Fig. 2 in association with the line 13 extending to the substation D, this apparatus includes a control device which is substantially identical in construction and arrangement with the corresponding device illustrated in Fig. 1 and included in the call forwarding apparatus associated with the substation B. For this reason, corresponding elements of the two control devices have been indicated in the two figures of the drawing by reference characters having the same tens and units digits but different hundreds digits. It will be noted that the only difference between the two control devices is that

in the arrangement illustrated in Fig. 2 the spring pile associated with the control cam 208 comprises only two contact springs 236 and 238, whereas the corresponding spring pile 110 embodied in the control device shown in Fig. 1 includes an additional contact spring 137. In the Fig. 2 arrangement, no auxiliary line between the substation arranged for call forwarding service and the central exchange switching apparatus is required, the switches utilized in forwarding a call from the line 13 to another of the substations of the system being directly controlled through the provision of apparatus for transmitting over the line 13 alternating current impulses designating the substation to which the call is to be forwarded. This apparatus, as provided at the substation D, comprises, in addition to the control device mentioned above, an alternating current start relay 220 for initiating operation of the control device and an alternating current relay 240 which is operative to connect the conductors of the line 13 to an alternating current pulsing circuit which includes a condenser 243 and the secondary winding of a voltage stepdown transformer 244. This alternating pulsing circuit is arranged to be controlled by the contact springs 210, 201 and 209 of the control device in the manner more fully explained subsequently.

For the purpose of repeating alternating current pulses transmitted from the substation D as direct current impulses over the line 13 to the automatic switching apparatus provided in the line terminating exchange, there is provided in the exchange in association with this line a special line circuit 30. More particularly, the line 13 is divided at the main distributing frame of the exchange into two normally connected line sections 13c and 13d, the first of which extends to the substation D and the second of which extends to the automatic switching apparatus provided in the exchange. Briefly described, the special line circuit 30 comprises an alternating current relay 250 which is normally bridged across the conductors of the line section 13c in series with a condenser 252 and is arranged to operate in response to ringing current transmitted over the line. The apparatus 30 further comprises a slow-to-release hold relay 255, a switching relay 260, an alternating current pulsing relay 265, a slow-to-release line switching relay 270 and a slow-to-release pulse responsive relay 275. There is also provided a repeating coil 223 which corresponds to the repeating coil 123 of the Fig. 1 arrangement, and a polarized back bridge relay 230 of the permanent magnet type which corresponds to the back bridge relay 130 embodied in circuits shown in Fig. 1.

Referring now to the operation of the call forwarding apparatus illustrated in Fig. 2, it will be apparent that so long as the station selecting element 202 of the control device occupies its normal position, the alternating current relay 220 is effectively disconnected from the conductors of the line 13 and cannot respond to ringing current transmitted over this line. With the apparatus in this condition if a call originating at the substation A, for example, is forwarded by way of the line 10, the line switch 14, the selector switch 19 and the connector switch 21 to the line 13 at a time when the latter line is idle, ringing current is projected over the line 13 by the control apparatus embodied in the connector switch 21 immediately following the

idle condition of the line. A portion of the ringing current traverses the winding of the relay 250 over a circuit which may partially be traced as extending by way of the armature 271, the armature 261, the condenser 252, the winding of the relay 250, the armature 262 and the armature 272. Each time this relay is energized by the ringing current it operates to complete, at its armature 251, an obvious circuit for energizing the slow-to-release hold relay 255. The relay 255, upon operating, prepares, at its armature 256, a circuit for energizing the relay 260. This latter circuit, which extends by way of the armature 251, is completed at the end of each ringing interval in response to the release of the relay 250. Upon operating, the relay 260 connects the winding of the alternating current relay 265 across the conductors of the line 13 in series with the condenser 267. Substantially simultaneously with the completion of the operating circuit for the relay 260, the operating circuit for the slow-to-release relay 255 is interrupted. The period between ringing intervals is such that the relay 255 restores to cause the restoration of the relay 260 shortly following the end of each ringing interval and before the next ringing interval occurs. Accordingly, the relays 250, 255 and 260 sequentially respond to each splash of ringing current transmitted over the line 13, but perform no useful function and do not function to cause the operation of any of the other relays embodied in the line circuit 30. When the call is answered at the called substation D to cause the operation of the ring cut-off relay provided in the connector switch 21, thereby to terminate the ringing operation, the three relays 250, 255 and 260 are caused to restore. These relays remain in their respective restored positions until another call is routed to the line 13.

If the call originating at the substation A is forwarded through the automatic switches 14, 19 and 21 to the line 13 at a time when the station selecting element occupies one of its off-normal positions, the call forwarding apparatus illustrated in Fig. 2 operates to cause the call to be forwarded to the substation corresponding to the off-normal position occupied by the station selecting element. For example, if the element 202 is set in the off-normal position corresponding to the substation B, the shunt springs 201 are positioned to be controlled by the cam 200 and the contact springs 204 are engaged so that the relay 220 is bridged across the conductors of the line 13. With the apparatus in this condition, if ringing current is projected over the line 13 the relays 250 and 255 are caused to operate in the manner explained above. In addition, the alternating current relay 220 is energized by a portion of the ringing current, the circuit traversed by this current extending by way of the armature 271, the line conductor 13a, the armature 242, the condenser 222, the winding of the relay 220, the contact springs 204, the armature 241, the line conductor 13b and the armature 272. When energized at the beginning of the first interval during which ringing current is transmitted over the line 13, the relay 220 operates to complete, at its armature 221 and the associated working contact, a circuit for energizing the motor 211, this circuit extending from one terminal of the alternating current supply source through the windings of the motor 211 and by way of the armature 221 to the opposite terminal of the current source. Operation of the motor is thus started to initiate a cycle of operation of

the control device. During the initial rotary movement of the control cam 207 carried by the shaft 212, the springs 235 are closed to complete an obvious secondary circuit for energizing the motor 211, whereby operation of the motor is continued after the release of the relay 220 at the end of the first ringing period. At the contact springs 234 a circuit is prepared for connecting the primary winding of the transformer 244 across the conductors of the alternating current supply source in parallel with the winding of the alternating current relay 240. At the end of the first ringing interval, the relays 220 and 250 are deenergized and restored. The relay 250, upon restoring, completes the operating circuit for the relay 260, which latter relay in turn operates its armatures 261 and 262 to connect the winding of the relay 265 across the conductors of the line section 13c. Upon restoring, the relay 220 opens, at its armature 221 and the associated working contact, the initially completed circuit for energizing the motor 211. At its armature 221 and the resting contact associated therewith, the relay 220 completes the above-mentioned circuit for energizing the relay 240 and the primary winding of the transformer 244 in parallel. This circuit may be traced as extending from one terminal of the alternating current supply source by way of the contact springs 235 to the armature 221 where it divides; one branch extending through the primary winding of the transformer 244 and the contact springs 234 to the opposite terminal of the current supply source and the other branch extending by way of the condenser 245, the winding of the relay 240 and the contact springs 234 to the opposite terminal of the current supply source. When energized over this circuit, the relay 240 operates to open, at the armatures 241 and 242 and their respective associated resting contacts, two points in the above-traced circuit for energizing the relay 220. At these same armatures and their respective associated working contacts, the relay 240 completes the previously mentioned circuit for energizing the pulsing relay 265, this circuit extending from the upper terminal of the secondary winding of the transformer 244 by way of the armature 242, the line conductor 13a, the armature 261, the condenser 267', the winding of the relay 265, the armature 262, the conductor 13b, the armature 241, the condenser 243 and the contact springs 218 to the lower terminal of the transformer secondary winding. Upon operating, the relay 265 completes, at its armature 266, a circuit for energizing the slow-to-release relay 270, this circuit extending from ground at the armature 232 by way of the armature 266 and the winding of the relay 270 to battery. At its armature 267, the relay 265 completes a calling loop circuit including the repeater coil windings 226 and 227 and the winding of the polarized relay 230, and extending to the line switch 24. The relay 270, upon operating, completes, at its armature 273, an obvious holding circuit for the relay 260, whereby the latter relay is held energized following the release of the relay 255 which occurs shortly after the operation of the relay 270. At its armatures 271 and 272, the relay 270 disconnects the line section 13d from the line section 13c, thereby to prevent the alternating current impulses transmitted over the line section 13c from being transmitted back over the calling end of the connection. At these same armatures and their respective associated working contacts the relay 270 partially completes a

connection between the line section 13d and the repeater coil windings 224 and 225. At its armature 274, the relay 270 prepares a circuit for energizing the slow-to-release relay 275.

5 When the relay 265 operates to complete the above-mentioned loop circuit extending between the repeater coil 223 and the line switch 24, this line switch operates to seize an idle one of the selector switches, such, for example, as the selector switch 13, and to extend the loop circuit thereto. The direction of current flow over this loop circuit is such that the polarized relay 230 does not operate at this time. Following the operation of the relay 270, the relays embodied in 10 the line circuit 30 are conditioned to respond to alternating current impulses transmitted thereto from the substation D over the line 13. In this regard it is pointed out that the transmission of alternating current impulses to the line circuit 30 is delayed for an appreciable time interval after the above-traced circuit is completed for 15 energizing the relay 265. This time interval is necessary in order to give the line switch 24 ample opportunity to select an idle one of the selector switches to which it has access. To this end, the spring 238 is held in engagement with 20 its associated spring 236, to maintain the pulsing springs 206 and the shunt springs 201 short circuited, during the interval required for the cam 208 to rotate through an angle of approximately 45 degrees corresponding to rotation of the cam 200 through an angle of approximately 135 degrees. At the end of this interval, the cam follows 25 lower portion of the spring 238 drops into the notch 208a formed in the peripheral surface of the cam 208 so that the pulsing springs 206, as shunted by the shunt springs 201, are actively included in the above-traced circuit over which the pulsing relay 265 is energized. The manner 30 in which the pulsing springs 206 and the shunt springs 201 cooperate to interrupt this circuit in accordance with the impulses of the impulse digits determined by the respective lengths of the notches 208a, 208b and 208c is exactly the same 35 as described above with reference to the operation of the control device illustrated in Fig. 1. These notches are formed of such lengths that the impulses of the directory number designating the substation B are transmitted over the line 40 section 13c to the pulsing relay 265. The relay 265, through operation of its armature 267, functions to repeat these impulses over the calling loop circuit to the automatic switching apparatus utilized in forwarding the call. When the 45 relay 265 restores at the beginning of the first impulse of each digit, it opens, at its armature 266, the above-traced operating circuit for the relay 270. At this same armature, the relay 265 completes a circuit for energizing the slow-to-release relay 275, this circuit extending from ground by way of the armatures 232, 266, 274 and the winding of the relay 275 to battery. Upon 50 operating at the beginning of the first impulse of each digit, the relay 275 completes, at its armature 276, an obvious path for short-circuiting the series path including the winding 226, the winding of the polarized relay 230 and the winding 227, thereby to exclude the impedance of these windings from the impulsive circuit over 55 which the impulses are transmitted to the automatic switching apparatus. Due to their slow-to-release characteristics, the relays 270 and 275 remain operated during impulsive. At the end of each digit the relay 265 is held operated for a sufficient time interval to permit the release of 60 65 70 75

the relay 275, which latter relay upon restoring, opens, at its armature 276 the above-described short-circuiting path.

The impulses of the first digit transmitted through operation of the control device provided at the substation D are repeated through operation of the pulsing relay 265 over the calling loop circuit to the first selector switch 18. This selector switch responds to the impulses of this digit by operating to select the group of connector switches having access to the line 11 to which the call is to be forwarded. During the interdigit pause between the first and second digits, the selector switch 18 operates to seize an idle one of the connector switches, such, for example, as the switch 20, in the selected group. The seized connector switch 20 responds to the impulses of the second and third digits by operating to select the line 11 in the exact manner previously explained with reference to the call routed from the substation A to the substation B. Assuming that the line 11 is idle at the time it is selected, the control apparatus of the connector switch 20 operates to transmit ringing current over this line for the purpose of energizing the signal device provided at the called substation B. The arrangement of the control device located at the substation D is similar to the arrangement of the control device illustrated in Fig. 1 in that a substantial time interval elapses between the end of the impulse transmission and the completion of the cycle of operation of the device. More particularly, the cam follower portion of the spring 238 is moved out of the notch 208a of the cam 208 shortly following the end of the last digit of impulses transmitted over the line 13. As a result, the springs 238 and 236 are moved into engagement to provide an auxiliary shunt across the pulsing springs 206 during continued operation of the control device and until the control cams 207 and 208 are returned to their respective home positions. This return movement requires an angular rotation of the cams 207 and 208 of approximately 225 degrees, thus providing a relatively long time interval during which the substation B may be signaled and the call answered. Assuming that the call is answered during this interval, a loop circuit is established between the called substation B and the connector switch 20, thereby to cause the operation of the ring cut-off and back bridge relays embodied in this connector switch. The back bridge relay of the connector switch 20, upon operating, reverses the direction of current flow over the loop circuit extending to the repeater coil 223 and including the winding of the polarized relay 230. As a result, the relay 230 operates to complete, at its armature 233, an obvious path shunting the pulsing springs controlled by the armature 267 of the pulsing relay 265. At its armature 231, the relay 230 interrupts the operating circuit for the relay 270 and completes an obvious holding circuit therefor. At its armature 231, the relay 230 completes a direct current path including the repeating coil windings 224 and 225 across the line conductors of the line section 13d. In response to this operation, the ring cut-off and back bridge relays embodied in the connector switch 21 are caused to operate in the manner previously explained, thus completing the desired talking circuit between the substation A and the substation B.

When the control device provided at the substation D completes its cycle of operation, the

motor 211 is deenergized and the two relays 240 and 265 are caused to restore. More particularly, when the cam 207 is returned to its home position, the springs 234 and 235 are respectively disengaged to open the secondary circuit for energizing the motor 211 and the above-traced circuit over which the winding of the relay 260 and the primary winding of the transformer 244 are connected in parallel across the alternating current supply source. Accordingly, the transformer 244 is deenergized and operation of the motor 211 is arrested. When the relay 240 is deenergized it restores to open two points in the above-traced circuit for energizing the relay 265 and reconnects the winding of the relay 220 across the conductors of the line 13. The relay 265, upon restoring, opens, at its armature 266, a further point in the operating circuit for the relay 270 and, at its armature 267, opens the path shunting the operated armature 233 of the back bridge relay 230.

The manner in which the connection as established between the substations A and B is released is substantially similar to the release of the connection established through operation of the call forwarding apparatus shown in Fig. 1. During the release of the connection and when the call is cleared out at the substation B the direction of current flow over the loop circuit, including the winding of the polarized relay 230, is reversed. As a result, this relay restores to open, at its armature 233, the loop circuit extending through the line switch 24 and the selector switch 18 to the connector switch 20 with the result that these switches are caused sequentially to restore in the order named. At its armature 232, the relay 230, upon restoring, opens the holding circuit for the relay 270 causing the latter relay and the relay 260 sequentially to restore. At its armature 231, the relay 230 opens a point in the loop circuit extending to the connector switch 21. Thus, the call forwarding apparatus illustrated in Fig. 2 is fully restored to normal.

The arrangement of the call forwarding apparatus shown in Fig. 2 is similar to the arrangement of the apparatus illustrated in Fig. 1 in that a call extended to the line 13 is repeatedly forwarded to the substation designated by the setting of the element 202 through repeated operations of the control device provided at the substation D until the call is answered or is abandoned at the calling substation. More particularly, if the call as forwarded to the substation B is not answered during the interval which elapses between the end of the last series of impulses transmitted over the line 13 and the end of the cycle of operation of the control device, the switch train through which the call is forwarded to the substation B is released. Thus, when the cam 207 is returned to its home position the contact springs 234 and 235 are respectively disengaged so that the relays 240 and 265 are caused to restore in the manner previously explained. Under the circumstances described, the back bridge relay 230 is not operated. Accordingly, the relay 265, upon restoring, interrupts the operating circuit for the relay 270, causing the relays 270 and 260 sequentially to restore. At its armature 267, the relay 265, upon restoring, also interrupts the loop circuit extending by way of the line switch 24 and the selector switch 18 to the operated connector switch 20. In response to this operation, the switches 20, 18 and 24 are caused sequentially to restore in the order named,

thus releasing the connection over which the call was initially forwarded to the substation B. If required, the relay 270 may be equipped with a dash pot or other suitable release retarding device in order to prevent the release of this relay before the switches 20, 18 and 24 are fully released. This release retarding device should be of such type that the relay 270 is fast-to-operate when energized. The relay 270, upon restoring, reconnects the line section 13d to the line section 13c so that if the call has not been abandoned, ringing current is again transmitted over the line section 13c to cause the reoperation of the two relays 250 and 220. Hence, a new cycle of operation of the control device is initiated. From this point on, the manner in which the call is again forwarded through the automatic switching apparatus to the substation B is exactly the same as described above.

If the call is abandoned at the calling substation A during a cycle of operation of the control device provided at the substation D, this device continues to operate until the cycle of operation is ended, after which the call forwarding apparatus is released. In this regard, it will be apparent that if the call is abandoned while the control device is in operation and the call is then answered at the substation B during the last part of the operating cycle of the control device, the answering party will be informed by the failure of the calling party to answer, that the call has been abandoned and may then condition the apparatus to be released at the end of the cycle of operation of the control device by restoring his receiver to its supporting hook or cradle. In the event the cycle of operation of the control device is completed before the answering party hangs up, the manner in which the three relays 230, 270 and 260, embodied in the line circuit 30, are released when the connection is cleared out at substation B is exactly the same as described above. In the event the call is not answered or is answered and released after the call is abandoned but before the cycle of operation of the control device is ended, the call forwarding apparatus is restored to normal immediately the cam 207 is returned to its home position. In response to this operation, the motor 211, the relay 240 and the transformer 244, are all deenergized in the manner set forth above. In addition, the relay 265 is caused to restore to interrupt the loop circuit extending through the line switch 24 and to open the operating circuit for the relay 270. Thus, the relays 270 and 260 are caused sequentially to restore and the switch train through which the call was forwarded to the line 11 is released. With the arrangement illustrated in Fig. 2, a call routed to the line 13 from another line of the system cannot be answered at the substation D if the call forwarding apparatus is conditioned for operation. Thus, immediately after the first interval during which ringing current is projected over the line 13 the relay 270 is caused to operate to disconnect the line section 13d from the line section 13c. Hence, ringing current is only transmitted over the line section 13c for one short interval and no talking circuit can be completed between the substation D and the connector switch through which the connection is routed to the line 13.

While there has been described what are at present considered to be the preferred embodiments of the invention, it will be understood that various modifications may be made therein, and

it is contemplated to cover in the appended claims all such modifications as fall within the true spirit and scope of the invention.

What is claimed is:

- 5 1. In an automatic telephone system including a plurality of substations and means comprising automatic switching apparatus for setting up connections between said substations, a line extending to one of said substations, said automatic switching apparatus including a connector switch operative to seize said line and to transmit ringing current thereover in routing a call to said one substation, call forwarding apparatus associated with said one line and operative directly to control said automatic switching apparatus to route a call incoming to said line through said automatic switching apparatus to any one of a plurality of other substations, means responsive to ringing current transmitted over said line for initiating the operation of said apparatus, and means operative in response to the answering of said call at said other substation for terminating the ringing operation of said connector switch.
- 10 2. In an automatic telephone system including a plurality of substations and means comprising automatic switching apparatus for setting up connections between said substations, a line extending to one of said substations, said automatic switching apparatus including a connector switch operative to seize said line and to transmit ringing current thereover in routing a call to said one substation, call forwarding apparatus comprising a cyclically operative device associated with said line and operative to transmit to said automatic switching apparatus the impulses of the directory number designating another of said substations, a motor for driving said device, means responsive to ringing current transmitted over said line for initiating the operation of said motor, means responsive to the initial operation of said device for maintaining the operation of said motor until the cycle of operation of said device is completed, said automatic switching apparatus including automatic switches operative to extend a connection from said line to said other substation in response to the impulses transmitted thereto from said device, and means operative to terminate the ringing operation of said connector switch when the call forwarded to said other substation over said last-named connection is answered.
- 15 3. In an automatic telephone system including a plurality of substations and means comprising impulse responsive automatic switching apparatus for setting up connections between said substations, a line extending to one of said substations, a relay adapted to be bridged across the conductors of said line to respond to ringing current transmitted to said one substation on calls incoming thereto, call forwarding apparatus comprising a cyclically operative device associated with said line and operative to transmit to said automatic switching apparatus the impulses of the directory number designating another of said substations, a motor for driving said device, a first circuit for energizing said motor, said first circuit being completed in response to operation of said relay, a second circuit for energizing said motor, said second circuit being completed in response to the initial operation of said device, said automatic switching apparatus including automatic switches operative to extend a connection from said one line to said other substation in response to the impulses trans-

mitted thereto from said device, means operative to interrupt said first circuit when the call forwarded to said other substation over said last-named connection is answered, and means controlled by said device for interrupting said second circuit after said device has completed a cycle of operation.

4. In an automatic telephone system including a plurality of substations and means comprising impulse responsive automatic switching apparatus for setting up connections between said substations, a line extending to one of said substations, a relay and a condenser connected in series and adapted to be bridged across the conductors of said line, whereby said relay responds to ringing current transmitted to said substation on calls incoming to said one substation, said automatic switching apparatus including a connector switch operative to seize said line and to transmit ringing current thereover in routing a call to said one substation; call forwarding apparatus comprising a cyclically operative device associated with said line and operative to transmit to said automatic switching apparatus the impulses of the directory number designating another of said substations, a motor for driving said device, a first circuit for energizing said motor, said first circuit being completed in response to operation of said relay, a second circuit for energizing said motor, said second circuit being completed in response to the initial operation of said device, said automatic switching apparatus including automatic switches operative to extend a connection from said line to said other substation in response to the impulses transmitted thereto from said device, means operative to short-circuit said condenser, thereby to cause the ringing operation of said connector switch to be terminated and also operative to interrupt said first circuit when the call forwarded to said other substation over said last-named connection is answered, and means controlled by said device for interrupting said second circuit after said device has completed a cycle of operation.

5. In an automatic telephone system including a plurality of substations and means comprising impulse responsive automatic switching apparatus for setting up connections between said substations, call forwarding apparatus comprising a cyclically operative device associated with one of said substations and operative to transmit to said automatic switching apparatus the impulses of the directory number designating another of said substations, said device including an impulsing control element and a switch release control element, a motor for driving said device, means responsive to a call routed to said one substation for initiating the operation of said motor, and means controlled by said switch release control element for maintaining the operation of said motor until the cycle of operation of said device is ended, said automatic switching apparatus including automatic switches operative to extend a connection to said other substation in response to the impulses transmitted thereto from said device, and said control elements being so constructed and arranged that said switches are held operated for an interval after said impulse transmission is ended.

6. In an automatic telephone system including a plurality of substations and means comprising impulse responsive automatic switching apparatus for setting up connections between said sub-

stations, call forwarding apparatus comprising a cyclically operative device associated with one of said substations and operative to transmit to said automatic switching apparatus the impulses of the directory number designating another of said substations, said device including an impulsing control element and a switch release control element, a motor for driving said device, means responsive to a call routed to said one substation for initiating the operation of said motor, and means controlled by said switch release control element for maintaining the operation of said motor until the cycle of operation of said device is ended, said automatic switching apparatus including automatic switches operative to extend a connection to said other substation in response to the impulses transmitted thereto from said device, said control elements being so constructed and arranged that said switches are held operated for an interval after said impulse transmission is ended, and means operative in the event the call as forwarded to said other substation over said last-named connection is answered during said interval for holding said switches operated independently of said device.

7. In an automatic telephone system including a plurality of substations and means comprising impulse responsive automatic switching apparatus for setting up connections between said substations, call forwarding apparatus comprising a device provided at one of said substations and including a plurality of control elements individually corresponding to certain of the other substations of said system, a station selecting element having a normal position and operative to off-normal positions individually corresponding to said control elements, and pulsing means adapted to be controlled by any one of said control elements for transmitting to said automatic switching apparatus the impulses of the directory number designating the substation corresponding to the off-normal position occupied by said station selecting element, a motor for driving said device, a device for initiating the operation of said motor, and means responsive to operation of said station selecting element to any one of said off-normal positions for conditioning said last-named device to operate in response to a call routed to said one substation.

8. In an automatic telephone system including a plurality of substations and means comprising impulse responsive automatic switching apparatus for setting up connections between said substations, a line extending to one of said substations, call forwarding apparatus comprising a device provided at said one substation and including a plurality of control elements individually corresponding to certain of the other substations of the system, a station selecting element having a normal position and operative to off-normal positions individually corresponding to said control elements, and pulsing means adapted to be controlled by any one of said control elements for transmitting to said automatic switching apparatus the impulses of the directory number designating the substation corresponding to the off-normal position occupied by said station selecting element, a motor for driving said device, a relay adapted to be bridged across the conductors of said line to respond to ringing current transmitted over said line, a circuit for energizing said motor, means controlled by said relay for completing said circuit, and means operative to bridge said relay across the conduc-

tors of said line in response to operation of said station selecting element to one of said off-normal positions.

9. In an automatic telephone system including a plurality of substations and means comprising impulse responsive automatic switching apparatus for setting up connections between said substations, a line extending to one of said substations, call forwarding apparatus comprising a cyclically operative device provided at said one substation and including a plurality of control elements individually corresponding to certain of the other substations of the system, a station selecting element having a normal position and operative to off-normal positions individually corresponding to said control elements, and pulsing means adapted to be controlled by any one of said control elements for transmitting to said automatic switching apparatus the impulses of the directory number designating the substation corresponding to the off-normal position occupied by said station selecting element, a motor for driving said device, a relay adapted to be bridged across the conductors of said line to respond to ringing current transmitted over said line, a circuit for energizing said motor, means controlled by said relay for completing said circuit, means operative to bridge said relay across the conductors of said line in response to operation of said station selecting element to one of said off-normal positions, a second circuit for energizing said motor, and means operated during the initial operation of said device for completing said second circuit and for maintaining said second circuit completed until the cycle of operation of said device is ended.

10. In an automatic telephone system, a plurality of substations, means comprising automatic switching apparatus for setting up connections between said substations, a line extending to one of said substations, and call forwarding apparatus comprising means automatically operative when an incoming call is present on said one line for repeatedly forwarding said call through said automatic switching apparatus to another of said substations until said call is abandoned or is answered at said other substation.

11. In an automatic telephone system including a plurality of substations and means comprising impulse responsive automatic switching apparatus for setting up connections between said substations, a line extending to one of said substations, call forwarding apparatus comprising a cyclically operating device for transmitting to said automatic switching apparatus the impulses of the directory number designating another of said substations during each cycle of operation thereof, and means operative when an incoming call is present on said one line for causing said device to operate through repeated cycles, thereby repeatedly to forward said call to said other substation, until said call is abandoned or is answered at said other substation.

12. In an automatic telephone system including a plurality of substations and means comprising impulse responsive automatic switching apparatus for setting up connections between said substations, a line extending between said automatic switching apparatus and one of said substations, call forwarding means comprising apparatus operative to cause a connection to be extended from said line through said automatic switching apparatus to another of said substations

tions in response to alternating current impulses transmitted thereto, and means automatically operative in response to the presence of an incoming call on said line for transmitting alternating current pulses to said last-mentioned apparatus.

13. In an automatic telephone system including a plurality of substations and means comprising impulse responsive automatic switching apparatus for setting up connections between said substations, a line extending between said automatic switching apparatus and one of said substations, call forwarding apparatus comprising an impulsing device at one of said substations, means controlled by said device for transmitting over said line alternating current impulses corresponding to the directory number designating another of said substations, apparatus operative in response to said alternating current impulses for causing a connection to be extended from said line through said automatic switching apparatus to said other substation, a motor for driving said device, and means operative in response to the presence of an incoming call on said line for initiating the operation of said motor.

14. In an automatic telephone system including a plurality of substations and means comprising impulse responsive automatic switching apparatus for setting up connections between said substations, a line extending between said automatic switching apparatus and one of said substations, call forwarding apparatus comprising an impulsing device at one of said stations; said impulsing device including a plurality of control elements individually corresponding to certain of the other substations of the system, a station selecting element having a normal position and operative to off-normal positions individually corresponding to said control elements, and means for transmitting over said line alternating current impulses designating the substation corresponding to the off-normal position occupied by said station selecting element; apparatus operative in response to said alternating current impulses for causing a connection to be extended from said line through said automatic switching apparatus to the substation designated by the position occupied by said station selecting element, a motor for driving said device, a circuit for energizing said motor, a device operative to complete said circuit, and means responsive to operation of said station selecting element to one of said off-normal positions for conditioning said last-named device to operate in response to a call routed to said one substation.

15. In an automatic telephone system including a plurality of substations and means comprising impulse responsive automatic switching apparatus for setting up connections between said substations, a line extending from said automatic switching apparatus to one of said substations, call forwarding apparatus comprising a device operative in response to ringing current transmitted over said line, means controlled by said device for transmitting over said line a long alternating current pulse followed by alternating current impulses corresponding to the directory number designating another of said substations, a pulsing relay adapted to be connected to said line to respond to said alternating current pulses and to repeat said impulses to said automatic switching apparatus, thereby to extend a connection from said line through said automatic switching apparatus to said other substation, and means controlled by ringing current transmitted

over said line for connecting said pulsing relay to said line.

16. In an automatic telephone system including a plurality of substations and means comprising impulse responsive automatic switching apparatus for setting up connections between said substations, a line extending from said automatic switching apparatus to one of said substations, a repeater including a first winding adapted to be connected across said line and a second winding adapted to be included in a calling loop circuit extending to said automatic switching apparatus, call forwarding apparatus comprising a device operative in response to ringing current transmitted over said line, means controlled by said device for transmitting over said line a long alternating current pulse followed by alternating current impulses corresponding to the directory number designating another of said substations, a pulsing relay adapted to be connected to said line to respond to said alternating current pulses, said pulsing relay being operative to complete said calling loop circuit and to repeat said impulses by way thereof to said automatic switching apparatus, whereby a connection is routed from said repeater through said automatic switching apparatus to said other substation, means responsive to operation of said pulsing relay for connecting said first winding to said line, and means controlled by ringing current transmitted over said line for connecting said pulsing relay to said line.

17. In an automatic telephone system including a plurality of substations and means comprising impulse responsive automatic switching apparatus for setting up connections between said substations, a line extending from said automatic switching apparatus to one of said substations, a repeater including a first winding adapted to be connected across said line and a second winding adapted to be included in a calling loop circuit extending to said automatic switching apparatus, call forwarding apparatus comprising a device operative in response to ringing current transmitted over said line, means controlled by said device for transmitting over said line a long alternating current pulse followed by alternating current impulses corresponding to the directory number designating another of said substations, a pulsing relay adapted to be connected to said line to respond to said alternating current pulses, said pulsing relay including contacts for completing said loop circuit and for repeating said impulses by way of said loop circuit to said automatic switching apparatus, whereby a connection is routed from said repeater through said automatic switching apparatus to said other substation, a hold relay operative to connect said first winding to said line in response to operation of said pulsing relay, a holding circuit for said hold relay, means controlled by ringing current transmitted over said line for connecting said pulsing relay to said line, and means operative when the call forwarded to said other substation is answered for completing said holding circuit and for shunting said pulsing contacts.

18. In an automatic telephone system including a plurality of substations and means comprising impulse responsive automatic switching apparatus for setting up connections between said substations, a line including two normally

connected sections, one of said sections extending to said automatic switching apparatus and the other of said sections extending to one of said substations, a repeater including a first winding adapted to be connected to said one line section and a second winding adapted to be included in a calling loop circuit extending to said automatic switching apparatus, call forwarding apparatus comprising a device operative in response to ringing current transmitted over said line, means controlled by said device for transmitting over said other line section a relatively long alternating current pulse followed by alternating current impulses corresponding to the directory number designating another of said substations, a pulsing relay adapted to be connected to said other line section to respond to said alternating current pulses, means controlled by said pulsing relay for completing said calling loop circuit and for repeating said impulses by way of said calling loop circuit to said automatic switching apparatus, whereby a connection is routed from said repeater through said automatic switching apparatus to said other substation, means responsive to operation of said pulsing relay for disconnecting said one line section from said other line section and for connecting said one line section to said first winding, and means controlled by ringing current transmitted over said line for connecting said pulsing relay to said other line section.

19. In an automatic telephone system including a plurality of substations and means comprising impulse responsive automatic switching apparatus for setting up connections between said substations, a line including two normally connected sections, one of said sections extending to said automatic switching apparatus and the other of said sections extending to one of said substations, a repeater including a first winding adapted to be connected to said one line section and a second winding adapted to be included in a calling loop circuit extending to said automatic switching apparatus, call forwarding apparatus comprising a device operative in response to ringing current transmitted over said line, means controlled by said device for transmitting over said other line section a relatively long alternating current pulse followed by alternating current impulses corresponding to the directory number designating another of said substations, a pulsing relay adapted to be connected to said other line section to respond to said alternating current pulses, said pulsing relay including contacts for completing said loop circuit and for repeating said impulses by way of said calling loop circuit to said automatic switching apparatus, whereby a connection is extended from said repeater through said automatic switching apparatus to said other substation, a hold relay operative to prepare a connection between said one line section and said first winding in response to operation of said pulsing relay, a holding circuit for said hold relay, means controlled by ringing current transmitted over said line for connecting said pulsing relay to said other line section, and means operative when the call forwarded to said other substation is answered for completing said last-mentioned connection, completing said holding circuit and shunting said pulsing contacts.

JOHN WICKS.
